(57) **CLAIM**

The ornamental design for a tattoo needle cartridge, as shown and described.

DESCRIPTION

FIG. 1 is a perspective view of a tattoo needle cartridge showing my new design;

FIG. 2 is a front elevation view thereof;

FIG. 3 is a rear side elevation view thereof;

FIG. 4 is a right side elevation view thereof; the left side being a mirror image thereof;

FIG. 5 is a top plan view thereof;

FIG. 6 is a bottom plan view thereof;

FIG. 7 shows a perspective view of a second embodiment of my claimed design as depicted in FIGS. 1-6, the difference consisting of five needles organized in a round pattern instead of three needles organized in a round pattern;

FIG. 8 shows a front elevation view thereof;

FIG. 9 shows a rear elevation view thereof;

FIG. 10 is a right side elevation view thereof; the left side being a mirror image thereof;

FIG. 11 is a top plan view thereof;

FIG. 12 is a bottom plan view thereof;

FIG. 13 shows a perspective view of a third embodiment of my claimed design as depicted in FIGS. 1-6, the difference consisting of seven needles organized in a round pattern instead of three needles organized in a round pattern;

FIG. 14 shows a front elevation view thereof;

FIG. 15 shows a rear elevation view thereof;

FIG. 16 is a right side elevation view thereof; the left side being a mirror image thereof;

FIG. 17 is a top plan view thereof;

FIG. 18 is a bottom plan view thereof;

FIG. 19 shows a perspective view of a fourth embodiment of my claimed design as depicted in FIGS. 1-6, the difference consisting of six needles organized in a round pattern instead of three needles organized in a round pattern;

FIG. 20 shows a front elevation view thereof;

FIG. 21 shows a rear elevation view thereof;

FIG. 22 is a right side elevation view thereof; the left side being a mirror image thereof;
FIG. 23 is a top plan view thereof;
FIG. 24 is a bottom plan view thereof;
FIG. 25 shows a perspective view of a fifth embodiment of my claimed design as depicted in FIGS. 1-6, the difference consisting of an array of nine needles organized in a round pattern instead of three needles organized in a round pattern;
FIG. 26 shows a front elevation view thereof;
FIG. 27 shows a rear elevation view thereof;
FIG. 28 is a right side elevation view thereof; the left side being a mirror image thereof;
FIG. 29 is a top plan view thereof;
FIG. 30 is a bottom plan view thereof;
FIG. 31 shows a perspective view of a sixth embodiment of my claimed design as depicted in FIGS. 1-6, the difference consisting of an array of seven needles organized in two rows instead of three needles organized in a round pattern and a larger tip required by such;
FIG. 32 shows a front elevation view thereof;
FIG. 33 shows a rear elevation view thereof;
FIG. 34 is a right side elevation view thereof; the left side being a mirror image thereof;
FIG. 35 is a top plan view thereof;
FIG. 36 is a bottom plan view thereof;
FIG. 37 shows a perspective view of a seventh embodiment of my claimed design as depicted in FIGS. 1-6, the difference consisting of an array of seven needles organized in two rows with the needle points arced instead of three needles organized in a round pattern and a larger tip required by such;
FIG. 38 shows a front elevation view thereof;
FIG. 39 shows a rear elevation view thereof;
FIG. 40 is a right side elevation view thereof; the left side being a mirror image thereof;
FIG. 41 is a top plan view thereof;
FIG. 42 is a bottom plan view thereof;
FIG. 43 shows a perspective view of a eighth embodiment of my claimed design as depicted in FIGS. 1-6, the difference consisting of an array of nine needles organized in two rows instead of three needles organized in a round pattern and a larger tip required by such;
FIG. 44 shows a front elevation view thereof;
FIG. 45 shows a rear elevation view thereof;
FIG. 46 is a right side elevation view thereof; the left side being a mirror image thereof;
FIG. 47 is a top plan view thereof;
FIG. 48 is a bottom plan view thereof;

FIG. 49 shows a perspective view of a ninth embodiment of my claimed design as depicted in FIGS. 1-6, the difference consisting of an array of nine needles organized in two rows with the needle points arced instead of three needles organized in a round pattern and a larger tip required by such;
FIG. 50 shows a front elevation view thereof;
FIG. 51 shows a rear elevation view thereof;
FIG. 52 is a right side elevation view thereof; the left side being a mirror image thereof;
FIG. 53 is a top plan view thereof;
FIG. 54 is a bottom plan view thereof;
FIG. 55 shows a perspective view of a tenth embodiment of my claimed design as depicted in FIGS. 1-6, the difference consisting of an array of thirteen needles organized in two rows with the needle points arced instead of three needles organized in a round pattern and a larger tip required by such;
FIG. 56 shows a front elevation view thereof;
FIG. 57 shows a rear elevation view thereof;
FIG. 58 is a right side elevation view thereof; the left side being a mirror image thereof;
FIG. 59 is a top plan view thereof;
FIG. 60 is a bottom plan view thereof;
FIG. 61 shows a perspective view of a eleventh embodiment of my claimed design as depicted in FIGS. 1-6, the difference consisting of an array of fifteen needles organized in two rows with the needle points arced instead of three needles organized in a round pattern and a larger tip required by such;
FIG. 62 shows a front elevation view thereof;
FIG. 63 shows a rear elevation view thereof;
FIG. 64 is a right side elevation view thereof; the left side being a mirror image thereof;
FIG. 65 is a top plan view thereof;
FIG. 66 is a bottom plan view thereof;
FIG. 67 shows a perspective view of a 12th embodiment of my claimed design as depicted in FIGS. 1-6, the difference consisting of an array of thirteen smaller gauge needles organized in two rows instead of three needles organized in a round pattern and a larger tip required by such;
FIG. 68 shows a front elevation view thereof;
FIG. 69 shows a rear elevation view thereof;
FIG. 70 is a right side elevation view thereof; the left side being a mirror image thereof;
FIG. 71 is a top plan view thereof; and,
FIG. 72 is a bottom plan view thereof.
The broken lines depicting one or more needles and a base in all figures depicts environmental subject matter only and forms no part of the claimed design.
